TRACTOR

Edgar J. Rickel, Leawood, and Thomas D. Kernohan, Niles, Kans., assignors to Rickel, Inc., Kansas City, Mo., a corporation of Kansas

Continuation-in-part of design application Ser. No. 5,825, Feb. 15, 1967. This application Aug. 14, 1967, Ser. No. 8,255

Term of patent 14 years

(Cl. D14—3)

Fig. 1.

Fig. 3.

Fig. 2.

Fig. 4.

Fig. 5.

FIG. 1 is a front perspective view of a tractor embodying our design;

FIG. 2 is a front elevational view of same;

FIG. 3 is a rear perspective view of same;

FIG. 4 is a top plan view of same; and

FIG. 5 is a side elevational view of same taken from the side opposite that seen in FIG. 1.

The dominant features of our design reside in the portions shown in full lines.

This application is a continuation-in-part of our application Ser. No. D. 5,825, filed Feb. 15, 1967, and now abandoned, which in turn was a continuation-in-part of our application Ser. No. D. 2,577, filed June 6, 1966, and now abandoned.

We claim:

The ornamental design for a tractor, as shown and described.
